COMBINED COUPLING, VACUUM CLEANER SUCTION CONTROL AND TOOL HOLDER

Karl Eric Leinfelt, Solna, Sweden, assignor to Aktie-
bolaget Electrolux, Stockholm, Sweden, a corporation
of Sweden

Filed Nov. 14, 1966, Ser. No. 4,641

Claims priority, application Sweden May 16, 1966

Term of patent 14 years

(Cl. D9—2)

FIG. 1

FIG. 2

FIG. 3

FIG. 4

FIG. 5

FIG. 6

FIG. 7

FIG. 1 is a perspective view of a combined coupling vacuum cleaner suction control and tool holder showing my new design;

FIGS. 2 and 3 are respectively top and bottom plan views thereof;

FIG. 4 is a side elevational view thereof;

FIG. 5 is an end elevational view;

FIG. 6 is an opposite end elevational view; and

FIG. 7 is a sectional view taken at line 7-7 of FIG. 6.

I claim:

The ornamental design for a combined coupling, vacuum cleaner suction control and tool holder, as shown.
